Primary Examiner — Michael Aaron Pratt(74) *Attorney, Agent, or Firm* — Christensen, Fonder, Dardi & Herbert PLLC**CLAIM**

We claim the ornamental design for a rifle magazine loader portion, as shown and described.

DESCRIPTION

FIG. 1 is a perspective view of a rifle magazine loader portion showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines shown in the drawings illustrate structure or features which form no part of the claimed design.
